United States Patent

Des. 238,619

Patented Jan. 27, 1976

238,619

COMBINED VANITY CASE AND FINANCIAL ORGANIZER

Valerie Barad, Gardena, Calif., assignor to Theodor Manufacturing Corp., Gardena, Calif.

Filed Sept. 21, 1973, Ser. No. 399,757

Term of patent 14 years

Int. Cl. D3—01

U.S. Cl. D86—10 N

FIG. 1 is a perspective view of a combined vanity case and financial organizer showing my new design;

FIG. 2 is an elevational view showing the side opposite to that shown in FIG. 1;

FIG. 3 is an end elevational view; and

FIG. 4 is a bottom plan view.

I claim:

The design for a combined vanity case and financial organizer, as shown and described.
